Application June 13, 1955, Serial No. 36,491

Term of patent 14 years

(Cl. D30—1)

Figure 1 is a perspective view of a gun showing my new design;

Figure 2 is a side elevational view of the gunstock;

Figure 3 is a plan view of the gunstock;

Figure 4 is a sectional view taken along the line 4—4 of Figure 2;

Figure 5 is a front view of the gunstock; and

Figure 6 is a partial plan view of the gunstock showing the butt cap sectioned along the line 6—6 of Figure 2.

The characteristic features of the design reside in the gunstock shown in full lines.

I claim:

The ornamental design for a gun substantially as shown and described.
